ELECTRIC PLUG AND SOCKET
ORGANIZATIONRalph W. E. Moore, Pittsburgh, Pa., assignor to
National Electric Products Corporation, Pitts-
burgh, Pa., a corporation of Delaware

Application November 25, 1933, Serial No. 699,652

12 Claims. (Cl. 200—119)

This invention relates to an electric plug and socket organization which is particularly applicable to fuse plugs.

Fusing of electric circuits is widely accomplished by means of plug fuses which are screwed into electric sockets of conventional form. When a fuse burns out it is not uncommon for an unskilled and ill advised person to reestablish the circuit by inserting a coin or other conducting article into the socket. This, of course, leaves the circuit without any protection, and means have heretofore been devised for preventing such ill advised re-establishment of the circuit. A construction for this purpose is shown in the patent 15 to Schmidt 1,863,383 in which an adapter is inserted into the bottom of the fuse socket. This adapter has a contact which is normally held out of engagement with the bottom socket contact, the circuit only being established when the adapter contact is advanced into engagement with the bottom contact of the socket by the insertion of a special fuse.

Lighting companies are called upon to fuse sockets made by a wide variety of manufacturers 25 and these sockets vary considerably in the height of the bottom socket contact above the bottom of the socket. In some instances, the bottom socket contact is a screw head which projects quite a distance above the bottom of the socket, as shown in the Schmidt patent, and as shown in Fig. 10 of the accompanying drawings. In other instances, the bottom contact may be close to the bottom of the socket as shown in Fig. 1 of the accompanying drawings. Thus, in order that an adapter of the type shown in the Schmidt patent may properly cooperate with the sockets made by various manufacturers, it is necessary that the movable contact of the adapter have a very large range of movement. This can be done, but introduces 30 manufacturing difficulties.

The present invention is in some respects an improvement upon the construction disclosed in the Schmidt patent, an object of the invention being to provide a circuit breaking adapter which 45 may be used with the various types of commercial fuse sockets without providing for a long range of movement of the circuit breaking contact of the adapter.

Another object of the invention is to provide 50 a circuit breaking fuse plug adapter in which the circuit breaking contact of the adapter has the same range of movement regardless of the particular commercial socket into which it may be inserted.

Another object of the invention is to provide a

circuit breaker adapter construction in which adequate clearance of the circuit breaking contacts is assured regardless of the arrangement of socket contacts.

A further object of the invention is to provide 5 an adapter which will properly cooperate with, and be retained in, the screw shell of the commercial fuse sockets made by the various manufacturers.

Other objects of the invention are to improve 10 the construction of fuse plugs and adapters from both manufacturing and operating standpoints.

Fig. 1 is an enlarged central vertical section showing a fuse plug and adapter embodying the present invention, in place in a fuse socket. 15

Fig. 2 is an inverted sectional view, taken approximately on line 2—2 of Fig. 1.

Fig. 2a is a fragmentary detail section taken on the line 2a—2a of Fig. 2, the parts being right side up as in Fig. 1. 20

Fig. 3 is an enlarged plan view of an unassembled fuse body.

Fig. 4 is an elevation of the unassembled fuse body shown in Fig. 3.

Fig. 5 is an enlarged elevation, partially in section, showing an unassembled adapter body. 25

Fig. 6 is an enlarged fragmentary central vertical section of an unassembled fuse cap.

Fig. 7 is a greatly enlarged fragmentary section taken on the line 7—7 of Fig. 6. 30

Fig. 8 is a greatly enlarged fragmentary section taken on the line 8—8 of Fig. 4.

Fig. 9 is a greatly enlarged fragmentary section taken on the line 9—9 of Fig. 4.

Fig. 10 is an enlarged central vertical section showing a modified form of fuse and adapter embodying the present invention, assembled in a 35 socket.

Fig. 11 is an enlarged fragmentary vertical section showing a third specific form of fuse and 40 adapter embodying the present invention.

Fig. 12 is an enlarged central vertical section showing a fourth specific form of fuse and adapter embodying the present invention, assembled in a socket.

Fig. 13 is an inverted plan view of the adapter shown in Fig. 12, taken approximately on the line 13—13 of Fig. 12.

Reference will first be had to Fig. 1. The organization shown comprises a fuse socket (of one form of standard construction) designated as a whole by 12, an adapter designated as a whole by 20, and a fuse plug designated as a whole by 40. The socket 12 comprises an insulating base 13 (usually porcelain) which supports and surrounds 55

a sheet metal screw socket member 14 and a center or base contact 15. Suitable terminals are, of course, provided for making wiring connection to the socket shell 14 and the center contact 15, but 5 these are not shown since they are standard fuse socket features which form no part of the present invention.

The adapter 20 will now be described, reference 10 being had to Figs. 1, 2, and 5. The adapter is built about an adapter body 21 of molded insulating material which has upper and lower central recesses 22 and 23. The lower recess 23 is closed by an annular conical cap 24 of insulating material, which supports a metal center contact 25. 15 A thread 26 is molded about the periphery of the adapter body; and making a tight screw fit therewith is a threaded sheet metal sleeve 27 having an inwardly extending annular flange 28 which engages the cap 24. Thus, the sleeve 27 and the 20 cap 24 are fixedly secured to the adapter body 21. About the upper recess 22 there is an annular wall portion 38; and the outer face of the wall is provided with six vertical grooves 29. A centrally located threaded aperture 30 (Fig. 5) passes from 25 the upper recess 22 to the lower recess 23; and into it there is screwed a metal circuit making and breaking plug 31. Within the lower recess 23 there is a spiral spring 32 (of suitable hairspring 30 type) having its inner end passed diametrically through the bottom of plug 31, and its outer end 33 secured against rotation by being inserted into any one of four slots 34 that lead off from the side wall of recess 23. In assembly the spring is so tensioned that it rotatively biases plug 31 to normally 35 keeping plug 31 out of engagement with contact 25. Secured to body 21 is a barb 35 which projects through adapter sleeve 27, to engage socket 14 and thereby prevent removal of the 40 adapter from a socket into which it has been inserted.

The fuse plug is composed of a number of parts 45 all of which are shown in Fig. 1 and some of which are shown in Figs. 3, 4, and 6. In Figs. 3 and 4 there is shown a single molded piece of insulating material designated as a whole by 41, which may be conveniently termed the fuse plug body. This body has an exteriorly tapered annular wall portion 42 within which there is a fuse chamber 43. Through the bottom of the fuse chamber there is 50 a centrally located hole 44 and two circumferentially located holes 45. About the hole 44 there are four upstanding projections 46; and within the hole 44 there is a sheet metal clutch thimble 47 (Fig. 1) which is fixed to the body 41 by lower flange 48 and upper flange 49. To prevent relative rotation between the thimble 47 and the body 41, the metal of the upper flange 49 is pressed 55 down between the vertical projections 46 (Fig. 3) as shown in Fig. 1.

60 The lower part of the body 41 is formed into inner and outer depending skirt portions 50 and 51 which fit, respectively, inside and outside of annular projection 38 of the adapter body 21. On the exterior of body 41 there is an annular ledge 52 having three vertical projections 53; and from this shoulder six grooves 54 run down the outer face of skirt 51.

A screw thimble 55 of sheet metal is telescoped 65 over the body 41 and has an interrupted inwardly projecting flange 56 which lies on top of the annular ledge 52 and rotatively interlocks with the vertical projections 53. A fuse link 57 passes from the clutch thimble 47, through a notch 58 in the top of the body wall 42, down a vertical groove 70 75 59 on the exterior of wall 42, and beneath the

flange 56 of screw thimble 55. This fuse link 57 may be soldered to the thimbles 47 and 55, as indicated at 47a and 55a.

Over the fuse body 41 there is telescoped a 10 molded fuse cap 60 of insulating material which has a depending skirt portion 61, a roughened edge 62, and a central aperture 64. The cap 60 is preferably cemented to the fuse body 41; and beads 41a, 41b, and 66 may be used (optionally) to 15 form a secure interlock with the cement. These beads may also be used (either with or without cement) to give a friction fit between the body 41 and the cap 60, notwithstanding slight manufacturing variations in size. Where a friction fit is 20 desired, the parts are so proportioned that in assembly the bead 66 (on the cap) clears the bead 41a (on the fuse plug body); and then as the parts approach the relation shown in Fig. 1, the beads 41a and 41b firmly engage the cap skirt 61 and the bead 66 firmly engages the vertical beads 41b, the 25 beads yielding or scraping away to take care of manufacturing variations in fit. Cut-outs 63 (Fig. 6) in the bottom of the cap skirt 61, engage projections 53 and rotatively interlock the fuse cap and the fuse body. Before the cap 60 is telescoped in place a window disc 65 of glass or other suitable material such as mica is placed on top of the body 41 and is clamped in place by the cap 60.

It will be seen that the structure provides for 30 easy assembly. In assembling the adapter 20, the spring 32 may be secured to plug 31 and then the plug may be inserted into the adapter body 21. The outer end 33 of the spring may then be moved circumferentially to give the spring the desired 35 tension and then be slipped into place in one of the slots 34. The cap 24 may be dropped into the bottom of sleeve 27; and then when the sleeve has been screwed onto the adapter body except for a fraction of a turn, the barb 35 may be inserted 40 through the slot in the sleeve and the sleeve screwed home to hold the cap 24 and the barb 35 in place.

In assembling the fuse plug, the thimble 47 may 45 be put in the body 41 and the fuse link 57 laid in place in the position shown in Fig. 1, being soldered at 47a. Then the screw thimble 55 may be telescoped over the body 41 and the solder applied at 55a. Following this window 65 may be inserted and the cap 60 be forcibly telescoped 50 into place on the body 41, cement preferably being used between the cap and body.

In use the fuse plug is screwed into the adapter, 55 and then the assembly of plug and adapter is screwed into the fuse socket 12. The plug may, of course, be readily removed, but the barb 35 engages the screw shell 14 of the socket, thereby preventing removal of the adapter by an unauthorized person. In the absence of a fuse plug, the circuit making and breaking plug 31 is held by 60 spring 32 in an upward position where it is out of engagement with contact 25. Thus it will be difficult, if not impossible, for an unauthorized person tampering with the installation to bridge the circuit without inserting a fuse.

Each adapter 20 may be designed to receive 65 fuses of not over a certain given rating, and this rating may be permanently marked on the top surface of wall 38. For example, an adapter designed to be fused with not over a 15 ampere fuse 70 75 75 may have "15 amperes" molded on top of the wall 38. The fuse plugs of graduated rating have graduated thicknesses of skirt 51; and all fuse plugs which are of greater than 15 ampere capacity have the depending skirt portion 51 so

thick that it will not telescope over the wall 38 of a 15 ampere adapter, thereby preventing their insertion in a socket containing a 15 ampere adapter. Fuses of lower rating have the skirt 51 5 thinner than fuses of higher rating, thereby permitting their insertion into sockets containing adapters of higher (but not lower) rating. For example, 5, 10, and 15 ampere fuses can be inserted into sockets containing a 15 ampere adapter, but fuses of 20, 25, etc. amperes cannot be.

When a replacement fuse is inserted it is simply screwed into place in the sleeve 27 of the adapter; and the conical clutch end of thimble 47 engages the conical end of circuit making plug 31 and screws it down to the position shown in Fig. 1 of the drawings, thus completing the circuit. When the fuse blows the gases generated may escape through holes 45 to grooves 29 and out through grooves 54 and cut away areas 63.

As may be seen from Fig. 1 of the drawings, the thread which is rolled into the adapter sleeve 27 is of the same pitch as the thread in socket 14 and the thread of thimble 55, but is of greater depth from crown to root than either of these other threads. Thus the maximum external diameter of thimble 55 is less than the minimum internal diameter of socket 14 so that it will be impossible to insert the fuse into a socket not equipped with an adapter.

The vertical distances between the top of center contact 15 and both the bottom and top of the fuse socket vary considerably in sockets made by different manufacturers. There are sockets of different depths and there are differences in the height of the center contact above the bottom of the socket. For example, in Fig. 1 there is shown a low lying center contact which has its top surface close to the bottom of the socket, while in Fig. 10 there is shown a relatively high center contact which has its top surface quite a distance above the bottom of the socket. These variations cause no difficulty in the construction or use of the present invention. In the forms shown in Figs. 1, 10 and 11 the adapter is screwed directly against the bottom contact and in all forms shown the fuse plug is screwed into the adapter and not into the original fuse socket. In Fig. 1 circuit is made and broken between the adapter contact 25 and the plug 31, so that constant circuit breaking clearance is assured (when a fuse is removed) regardless of the height of the center contact 15 above the bottom of the socket.

In the sockets made by the various manufacturers there is also considerable variation in the screw shells 14. Some have a deep shell threaded for its entire depth as shown in Fig. 1; others have only a shallow shell; and still others have a shell which presents only a thread or two that are spaced way above the bottom of the socket. These variations also cause no difficulty with the plug and adapter of the present invention as the plug is not dependent upon the screw threads of the main socket, and the adapter has a long sleeve threaded throughout its entire length so that it can cooperate with socket threads either near the bottom of the socket or near the top of the socket.

The construction shown in Fig. 10 is so generally similar to that which has previously been described that it will only be necessary to point out the major differences between it and the construction of Fig. 1. The outer end of spring 71 which rotatively biases the circuit making plug 72 is formed into a vertically extending spring 75 loop 73, which is inserted into and frictionally

grips any one of several circumferentially positioned holes 74. The clutch engagement between the plug 72 and the fuse is just the reverse of that shown in Fig. 1 in that the male clutch member is carried by the fuse and the plug 72 is recessed to constitute a female clutch member. The body 75 of the fuse plug is molded about the clutch member 76; the inner end of the fuse link 77 being clamped to clutch member 76 by a sheet metal cup 78 that is forced into the clutch member. The cap 79 is cemented to the body 75. The fuse vents through passageways 76, 76a and 76b.

In Fig. 11 there is shown a construction in which the circuit making plug of the adapter 15 moves longitudinally without rotation of the plug being essential. A plug 90 is biased upwardly by a helical spring 91, but is adapted to be forced against lower contact 92 by direct thrust of a push member 93 carried by the fuse plug. The end of the push member 93 may have a nose that enters a recess in plug 90 for the purpose of breaking strips of tinfoil which may be placed over the adapter in an attempt to bridge a blown fuse. When the fuse plug is removed, the spring 91 retracts the circuit making plug 90 from the position shown in dotted lines to the position shown in solid lines. In assembly, the plug 90 and spring 91 may be inserted in the adapter body, and then the end of plug 90 may be riveted to a washer 94. The remainder of the assembly may follow that discussed in connection with Fig. 1, a barb being used if desired to prevent removal of the adapter from a socket.

The construction shown in Figs. 12 and 13 combines some of the features shown in the previous forms and presents certain different features. The construction of the fuse plug designated as a whole by 100 is preferably the same as that described in connection with Fig. 1 except for the adapter actuating member 101. This member is a hollow stamped drawn sheet metal thimble which is inserted from the bottom and has its upper end eyeleted or riveted over and between projections such as 46 (Fig. 3). The circuit making plug 102 of the adapter is arranged similarly to the plug 90 of Fig. 11, but the washer 103 that is riveted to it has lateral extension 104, 104 which slide in vertical grooves 105, 105. Thus as a fuse is inserted, plug 102 cannot rotate while member 101 does. The relative rotation between 101 and 102 as a fuse is being inserted is exceedingly effective in tearing and displacing strips of tinfoil which may be placed on top of the adapter in an attempt to bridge a blown fuse.

The screw thimble 106 is a tight screw fit with the adapter body 107 and, of course, a barb or the like may be used to retain the adapter in a socket. The circuit making plug 102 is adapted to directly engage the bottom socket contact, but constant circuit breaking clearance (regardless of the height of the center contact) is maintained, nevertheless. Aperture 108 is made so small that it cannot receive the center contact of any of the various commercial fuse sockets. Thus, the depth of insertion of the adapter into a socket is determined by top of the socket center contact, and hence the circuit breaking clearance will always be the distance between the bottom of the adapter and the bottom of plug 102 when retracted.

Of course, the invention may be embodied in various specific forms and the forms disclosed are merely illustrative, being the best forms in

which I have contemplated applying the invention.

I claim:—

5. A fuse organization comprising: a receptacle for a fuse plug, said receptacle having a pair of contacts; an adapter within the receptacle, said adapter having a first contact engaging one of the receptacle contacts, and a movable second contact normally biased into non-engaging position with respect to said first contact; and a fuse plug cooperable with the adapter to move said second contact into engagement with said first contact.
10. A fuse organization comprising: a receptacle for a fuse plug, said receptacle having a pair of contacts; an adapter within the receptacle, said adapter having a first contact engaging one of the receptacle contacts, and a movable second contact normally biased into non-engaging position with respect to said first contact; and a fuse plug cooperable with the adapter to move said second contact into engagement with said first contact; said adapter and plug being provided with interfitting formations which prevent the insertion of a fuse of undesired rating.
15. An electrical screw plug organization comprising: a socket having a sheet metal shell with screw threads pressed therein; an adapter having a sheet metal sleeve with screw threads pressed therein, said sleeve being screwed into said shell and the sleeve threads being of greater depth from crown to root than the shell threads; and a plug-like element screwed into said sleeve.
20. An electrical screw plug organization comprising: a socket having a sheet metal shell with screw threads pressed therein; an adapter having a sheet metal sleeve with screw threads pressed therein, said sleeve being screwed into said shell and the sleeve threads being of greater depth from crown to root than the shell threads; a plug-like element screwed into said sleeve; a circuit breaker within said adapter; and means carried by the plug to actuate said circuit breaker.
25. A circuit breaker for a cup-like electric socket having a bottom contact, comprising: a body insertable into the socket; a first contact carried by the body to engage said socket contact when the body is inserted; and a second contact carried by said body, said second contact being movable into and out of engagement with said first contact.
30. A circuit breaker for a cup-like electric socket having a bottom contact, comprising: a body insertable in the socket; a first contact carried by the body to engage said socket contact when the body is inserted; a movable second contact carried by said body; and a spring operable to bias said second contact into non-engaging position with respect to said first contact, said second contact being movable against pressure of the spring to engage said first contact.
35. A fuse organization comprising: a screw socket having a bottom contact; an adapter having a body portion carrying a first contact which engages said socket contact and having a second reciprocating contact, the second contact being normally spring biased into non-engaging position with respect to said first contact; and a fuse plug screwed into said adapter, said plug having means which pushes said second contact into engagement with said first contact.
40. A circuit breaker for a cup-like electric socket having a contact, comprising: a body insertable into the socket; a first contact carried by the body to engage said socket contact when the body is inserted; and a second contact carried by said body, said second contact being movable into and out of engagement with said first contact.
45. A fuse organization comprising: a screw socket having a bottom contact; a circuit breaking adapter to be screwed into said socket, the forward end of the adapter being shaped to engage the surface of said bottom contact to limit the insertion of the adapter in the socket, and the adapter having a movable contact normally biased into constant circuit breaking clearance with respect to said bottom contact; and a screw plug fuse cooperable with the adapter to advance said movable contact into engagement with said bottom contact.
50. A fuse organization comprising: a screw socket having a bottom contact; a circuit breaking adapter to be screwed into said socket, the depth of insertion of the adapter being determined by the top surface of said bottom contact, and the adapter having a reciprocating contact normally biased into constant circuit breaking clearance with respect to said bottom contact; and a screw plug fuse having means to engage said reciprocating contact and advance it into engagement with said bottom contact.

RALPH W. E. MOORE.
